UNITED STATES PATENT OFFICE.

WOOD BINNING, OF GRAND RIVER, IOWA.

MOLD.

1,133,223.

Specification of Letters Patent. Patented Mar. 23, 1915.

Application filed December 12, 1912. Serial No. 736,385.

To all whom it may concern:

Be it known that I, WOOD BINNING, a citizen of the United States, residing at Grand River, in the county of Decatur and State of Iowa, have invented a new and useful Mold, of which the following is a specification.

This invention has reference to improvements in molds designed more particularly for the formation of concrete blocks, and its object is to provide a mold avoiding the use of a pallet for transferring the green block from the point of molding to the sand, and, at the same time, permitting the formation of a long, thin block.

By the present invention the mold is light and readily transferable, so that it is possible to produce a block much longer and of materially less thickness than heretofore and to permit the making of the blocks materially faster than where pallets are employed.

With a mold of the present invention the blocks as formed are long, relatively wide or high and thin and too frail to be carried on edge on a pallet, for in order to transfer a block on a pallet it must be made thick, short and low, hence requiring a larger amount of material with respect to the surface produced than with the present invention, by which latter there may be produced blocks especially adapted for hollow-wall buildings, light strong partitions, and curtain walls.

In actual practice a block containing the same surface as those heretofore constructed may be made with approximately one-half the material and the saving of nearly or quite two-thirds the labor.

With the present invention it is practicable to make blocks either straight or curved from one inch to four inches thick, and, if curved, for circles ranging from one foot to thirty feet in diameter. Moreover, the mold of the present invention will take a mixture as wet as a mold employing a pallet and the structure of the mold permits the taking of the mold itself with the inclosed molded block directly from the tamping table to the sand where the green block is readily deposited by the simple operation of opening the mold, and the latter is so constructed that the block is released, without injury, by a minimum opening movement of the mold. All this is brought about by providing a mold with two sides or members held together at

one end by a hinge, and at the other end by a latch or other suitable fastening device, and the structure is such that the mold is markedly rigid when latched together with the concrete mixture therein, so that despite the fact that the molded block is too thin and frail to permit the transference on a pallet, it may be readily transferred from the tamping table to the sand while still inclosed in the mold without injury and may be there deposited also without injury.

The invention will be best understood from a consideration of the following detailed description taken in connection with the accompanying drawings forming a part of this specification, with the further understanding that while the drawings show a practical form of the invention the latter is not confined to any exact conformity with the showing of the drawings but may be changed and modified so long as such changes and modifications mark no material departure from the salient features of the invention.

In the drawings:—Figure 1 is a perspective view of a mold constructed in accordance with the present invention and designed for the production of a long, thin, straight block. Fig. 2 is a section on the line 2—2 of Fig. 1. Fig. 3 is a section on the line 3—3 of Fig. 2. Fig. 4 is a section similar to that of Fig. 2 but showing the mold open and indicating a molded block in dotted lines. Fig. 5 is a longitudinal vertical section of a mold such as shown in Fig. 1 with the addition of a corrugated member for the production of ventilating blocks and also the addition of a strip for filling in a bead groove indicated in Figs. 1 and 3. Fig. 6 is a section on the line 6—6 of Fig. 5. Fig. 7 is a section similar to Fig. 6 except that the corrugated strip is omitted and a facing plate is shown applied to the mold. Fig. 8 is a perspective view of the bead eliminating strip shown in Figs. 5 and 6. Fig. 9 is a perspective view of the corrugated member shown in Figs. 5 and 6. Fig. 10 is a perspective view of the facing strip shown in Fig. 7. Fig. 11 is a perspective view of a curved mold form constructed on the same general lines as Fig. 1.

The mold box or body comprises two generally similar members each consisting of longitudinal strips 1, 2 with connecting end plates 3 and an intermediate longitudinal strip 4. The strips 1 and 2 may be of

substantially the same width, but the strips 1 are made considerably thicker than the strips 2, thus permitting the formation in the strip 1 of one member of a longitudinal groove or channel 5 extending from one end of the strip to a point adjacent to but spaced a distance from the other end of the strip.

Secured to corresponding ends of the strips 1 and 2 of one mold member and also to the corresponding plate 3 is an end board 6 projecting from what may be termed the inner face of the mold member in a direction substantially perpendicular thereto and of a length to reach to and overlap to an extent the corresponding end of the other mold member when the mold is closed, as will hereinafter appear.

The end board 6 of one mold member is connected to the corresponding plate 3 of the other mold member by hinges 7, these hinges constituting effectively a single hinge, that is, the two mold members are hinged together at one angle only, so that the mold may be said to have but a single hinge connection. The diagonally opposite plate 3 carries hasps 8, while the adjacent end board 6 of the other mold section is provided with staples 9 over which the hasps may engage to hold the mold sections in the closed position, in which position they may be retained by pins or any other suitable devices for the purpose. Fast to the plate 3 remote from that carrying the hasps, but belonging to the same mold section is a filler block 10 constituting that end of the mold chamber of the mold box corresponding to the end of the mold where the hinge connection is placed. This hinge connection is so disposed as to be at some considerable distance from the corresponding end of the mold chamber, and consequently the inner face of the filler block 10 will, when the mold is open, move rapidly away from a molded block lodged in the mold box.

It will be noted that the hinge connection is located on the outside of the mold at the angle formed by the end of end board 6, and the contiguous end of side plate 3, and because of this relation of the hinge to the parts which it connects, it is placed at least one inch out of the longitudinal line of the molded article. The least motion of the hinge after unlatching the mold would serve to completely release the molded block provided the hinge was stationary, but in actual practice, the hinge is not stationary, due to the vibration of the arm of the operator, and a quicker clearance is sought and attained by setting the hinge farther from the molded article, or the latter farther from the hinge, by means of the said filler block. The quicker clearance is desired to counteract the vibration mentioned above.

In order to provide side members for the mold chamber of suitable strength and yet

without materially adding to the weight of the mold, sheet metal members 11 are provided, these members being secured to the inner faces of the strips 1 and 2 and to the end boards 6, while the internal pressure of the cement mixture when placed in the mold box is resisted by the strips 4, so that the mold may be of extremely light construction and yet amply strong, for the various strips, plates and boards may be formed of wood which has the advantage of lightness and strength and those faces of the mold chamber against which the cement mixture contacts may be made of protected sheet metal such as galvanized iron, which has the further advantage of being non-adhesive to the cement mixture. Besides the plates 11, the top and bottom edges of the mold box may be provided with strips 12 of galvanized sheet metal, which have the further purpose of wear plates. The plate 11 of that member of the mold box provided with a groove or channel 5 is made to conform to such groove or channel, as best indicated in Figs. 1 and 3.

With a mold box as described the mold is closed and provides an elongated thin chamber into which the cement mixture or concrete is introduced, the mixture being of about the same consistency with respect to the amount of water present as is customarily employed, that is, being of a consistency customarily termed semi-dry. This mixture is tamped in the mold in the usual manner. In practice the mold may be of such size as to produce a block of, say, two to two and one-half inches thick, nine inches wide and thirty-two inches long, although these particular dimensions may vary considerably, but still the block is long in comparison to its thickness and is of such shape that if the attempt were made to transfer the block upon a pallet while the block is green, from the tamping table to the sand the block would simply collapse. However, a mold constructed as described is not only amply strong but so light, and the block is made so thin with respect to its other dimensions that the weight of the mold with the block therein permits the ready transference of the mold and block from the tamping table to the sand before the mold is opened, and without danger to the block. Not only is the mold strong, but it is particularly rigid, this being due to the comparatively wide longitudinal edge members 1 and 2 which impart rigidity to the mold without adding materially to the weight thereof, and further the single hinge connection permitting the opening and closing of the mold also contributes to the rigidity of the mold, thus making the transference of the mold with the block therein without the necessity of a pallet feasible. The filler block 10 also contributes to the rigidity of

the mold at the hinged end and, moreover, spaces the corresponding end of the block a sufficient distance from the hinge, which latter is located at one corner or angle of 5 the mold, so that when the mold is opened that end of the mold chamber determined by the block 10 is moved rapidly away from the molded article and there is no liability of injury to the corresponding end of the 10 molded article due to scraping of the hinged end of the mold chamber along the molded article, this latter trouble being common in molds where the hinges are closely related to the corresponding end of the mold chamber. 15

With a mold such as shown in Figs. 1 and 3 there is produced a straight, thin block of comparatively great width with respect to the thickness and along one edge 20 there is produced a bead corresponding to the groove or channel 5, such construction being advantageous for certain purposes. If it be desirable to produce a block of even thickness throughout omitting the bead, then 25 the groove or channel 5 is filled up by an appropriate strip 13 shown separately in Fig. 8, this strip having facings 14 formed of strips of suitably galvanized sheet metal where liable to contact with the concrete mixture. 30 The strip 13 may have perforations 15 at appropriate points for the passage of screws or other fastening devices serving to hold the strip removably in place.

For some purposes it is desirable that one 35 edge of the thin block have appropriately formed notches or recesses therein, and for such purpose there is provided a board 16 which may constitute a bottom board for the mold chamber and of an appropriate size 40 to receive the mold when closed, and this board carries suitably spaced blocks 17 preferably, though not necessarily, tapering from the board 16 to their free ends. These blocks 17 are of a size to fit snugly between 45 the side walls of the mold chamber, entering such chamber for an appropriate distance, while those faces of the blocks and of the board 16 presented toward the interior of the mold chamber and subject to contact 50 with the concrete mixture have a covering 18 of galvanized sheet metal. The arrangement of the recess forming bottom member for the mold chamber is shown in Figs. 5, 6 and 9. Again, it is desirable to provide 55 the blocks with ornamental faces which are designed to be exposed to view in a finished structure. For this last purpose there is provided a frame 19 of a size to fit snugly within the mold chamber against one face 60 plate 11, and this frame carries a facing 20 which may be more or less dished within the confines of the frame 19 to constitute a molding face which will produce any ornamental effect desired, and this portion 20 of 65 the facing structure may be formed of gal-

vanized sheet metal as are other parts of the mold where exposed to contact with the concrete mixture. The frame may be strengthened and protected by sheets 21 of metal and holes 22 are formed through the frame and 70 the metal sheets, wherever desirable for the attachment of the facing frame to the corresponding mold member. The facing frame 19 of course occupies some of the interior space of the mold chamber and 75 causes the production of a thinner block than when the facing structure is omitted.

While the foregoing description has been directed to what may be termed a straight mold, the structure is adapted to the production of curved blocks by making the mold appropriately curved, and such a mold is illustrated in Fig. 11. Since the structure of the curved mold may be in all respects like that of the straight mold of the 80 other figures except that the parts are curved instead of straight, no detailed description of this mold is deemed necessary. The showing of Fig. 11 may be considered 85 indicative of any suitable type of curved 90 mold which may differ quite markedly from the showing of Fig. 11, but in all instances the material features of the invention are retained even though the embodiments of the invention vary from the showing of the 95 drawings because of the different shapes of block which it may be desirable to produce.

The corrugated molding member illustrated separately in Fig. 9, the strip 13 illustrated separately in Fig. 8, and the facing member illustrated in Fig. 10 may be taken as indicative of any suitable means 100 introducible into the molding chamber for varying the article or articles to be produced, but the presence or absence of these 105 structures does not change the function of the mold which permits the production of thin blocks adapted to many building purposes and the construction of a mold so light and rigid as to permit the transfer 110 of such thin blocks while still in the green state without damage to the blocks.

The recess forming member 16-17 has the blocks 17 so related to the thickness of the mold chamber when the mold members 115 are close together that these blocks will be firmly clamped, wherefore the board 16 with the blocks 17 may be transported with the mold from the tamping table to the sand at which point the mold may be so 120 placed that the board 16 is uppermost before the mold is opened.

The particular advantage of the structure disclosed in Figs. 5, 6, and 9 is that by this construction of mold, I am enabled 125 to produce a long, thin block, having notches or recesses at one edge. A block of this construction is of particular advantage in the construction of corn cribs and other places where a ventilated structure is de- 130

sired, for the notches or recesses in the edge of the block provide openings in the structure for the passage of air.

What is claimed is:—

- 5 1. A mold structure freely open at the top and bottom and comprising two members, each comprising one side and one end of the mold structure, a single hinge connecting the side of one member with the adjacent end of the other member, a fastening 10 means for connecting the two members together, a board arranged exteriorly of the mold structure and separate therefrom and having greater dimensions than the latter and constituting a bottom board for the mold chamber, spaced blocks provided on the board and of a size to fit snugly between the walls of the two members, and means for fastening the members together, whereby the blocks are firmly clamped and the board having the blocks may be transported with the mold, the blocks enabling a concrete block to be formed with notches or recesses along one edge.
- 15 2. A mold structure freely open at the top and bottom and comprising two members, each comprising one side and one end of the mold structure, a single hinge connecting the side of one member with the adjacent end of the other member, a fastening means for connecting the two members together, a board arranged exteriorly of the mold structure and separate therefrom and having greater dimensions than the latter and constituting a bottom board for the mold chamber, spaced blocks provided on the board and of a size to fit snugly between the walls of the two members, and means for fastening the members together, whereby the blocks are firmly clamped and the board having the blocks may be transported with the mold, the blocks enabling a concrete block to be formed with notches or recesses along one edge.
- 20 3. A mold structure freely open at the top and bottom and comprising two members, each comprising one side and one end of the mold structure, a single hinge connecting the side of one member with the adjacent end of the other member, a fastening means for connecting the two members together, a board arranged exteriorly of the mold structure and separate therefrom and having greater dimensions than the latter and constituting a bottom board for the mold chamber, spaced blocks provided on the board and of a size to fit snugly between the walls of the two members, and means for fastening the members together, whereby the blocks are firmly clamped and the board having the blocks may be transported with the mold, the blocks enabling a concrete block to be formed with notches or recesses along one edge.

2. A mold structure freely open at the top and bottom and comprising two members, 25 a board arranged exteriorly of the mold structure and separate therefrom and having greater dimensions than the latter and constituting a bottom board for the mold chamber, spaced blocks provided on the board and of a size to fit snugly between the walls of the two members, and means for fastening the members together, whereby the blocks are firmly clamped and the board having the blocks may be transported with 30 the mold, the blocks enabling a concrete block to be formed with notches or recesses along one edge.

In testimony, that I claim the foregoing as my own, I have hereto affixed my signature in the presence of two witnesses.

WOOD BINNING.
